[57] **CLAIM**

The ornamental design for a food processor base, as shown and described.

DESCRIPTION

FIG. 1 is a perspective view of a food processor base embodying our new design;

FIG. 2 is a front end elevational view thereof;

FIG. 3 is a top plan view thereof;

FIG. 4 is a side elevational view of the side not visible in FIG. 1, the opposite side elevational view being substantially a mirror image thereof; and

FIG. 5 is a rear end elevational view thereof.
